Primary Examiner — T Chase Nelson*Assistant Examiner* — Kelly L Gross(74) *Attorney, Agent, or Firm* — Kim IP Law Group LLC(57) **CLAIM**

The ornamental design for a surgical implant extractor jaw, as shown and described.

DESCRIPTION

FIG. 1 is a perspective view of a surgical implant extractor jaw in accordance with the new design;

FIG. 2 is a left side view of the surgical implant extractor jaw of FIG. 1;

FIG. 3 is a right side view of the surgical implant extractor jaw of FIG. 1;

FIG. 4 is a front view of the surgical implant extractor jaw of FIG. 1;

FIG. 5 is a rear view of the surgical implant extractor jaw of FIG. 1;

FIG. 6 is a top view of the surgical implant extractor jaw of FIG. 1; and,

FIG. 7 is a bottom view of the surgical implant extractor jaw of FIG. 1.

The broken lines in the figures are directed towards portions of the surgical implant extractor jaw that form no part of the claimed design.

1 Claim, 6 Drawing Sheets(56)
